(57) **CLAIM**

The ornamental design for an LED lamp, as shown and described.

DESCRIPTION

FIG. 1 is a perspective view of an LED lamp in accordance with the present design;

FIG. 2 is a top plan view thereof;

FIG. 3 is a bottom plan view thereof; and,

FIG. 4 is a side view thereof, with the other sides being symmetrical.

The broken line portions of the drawings are for illustrative purposes only and form no part of the claimed design. Any shading forms no part of the claimed design and is provided to illustrate contour only and is not an indication of texture, gloss, and the like.
